FIG. 1 is a front perspective view of a combination five gallon bucket opener, showing the design;

FIG. 2 is a right side elevation view thereof;

FIG. 3 is a left side elevation view thereof;

FIG. 4 is a rear elevation view thereof;

FIG. 5 is a front elevation view thereof;

FIG. 6 is a top plan view thereof;

FIG. 7 is a bottom plan view thereof;

FIG. 8 is a left side elevation view thereof, shown in an environment of use; and,

FIG. 9 is a rear perspective view thereof, shown in an environment of use.

The broken lines in FIGS. 1-3, 8, and 9 are included for the purpose of illustrating unclaimed environment and form no part of the claimed design.
